UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR CARPETS.

SPECIFICATION forming part of Design No. 11,633, dated February 3, 1880.

Application filed January 5, 1880. Term of patent 3½ years.

To all whom it may concern:

Be it known that I, WALTER J. GADSBY, a subject of the Queen of Great Britain, residing at Boston, in the county of Suffolk and state of Massachusetts, have invented a new and original Design for Carpet, of which the following is a specification.

The nature of my design is fully shown in the accompanying photographic illustration, forming a part of this specification.

My design consists of the variously-ornamented irregular figures A, B, C, D, D', D'', F, G, H, and L, and fan-shaped figures

I, I', I'', J, J', J'', and K, all arranged, as shown, on an ornamented ground, M.

I claim—

The design for a carpet, substantially as shown and described.

In testimony whereof I have signed my name to this specification, in the presence of two subscribing witnesses, this 31st day of December, 1879.

WALTER J. GADSBY.
